(57) **CLAIM**

The ornamental design for an outdoor karaoke equipment as shown and described.

DESCRIPTION

FIG. 1 is a front view of an outdoor karaoke equipment according to the present application, showing our new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof;

FIG. 8 is a second perspective view thereof, shown in an open configuration; and,

FIG. 9 is an enlarged detail view of the indicated portion 9 of the outdoor karaoke equipment shown in FIG. 7.

The portions of the design surrounded in broken lines and shown in a lower contrast illustrate portions of the outdoor karaoke equipment that form no part of the claimed design. The dot-dash broken lines indicate cutoff boundaries for enlarged detail portion views and form no part of the claimed design.
